(57) **CLAIM**

The ornamental design for a can shaped speaker housing, as shown and described.

DESCRIPTION

FIG. 1 is a top perspective view of a can shaped speaker housing, showing our new design;

FIG. 2 is front elevation view thereof, and the rear elevation view is a mirror image of the front elevation view thereof; and,

FIG. 3 is a bottom plan view thereof.

The dot-dot-dash broken lines represent the bounds of the claimed design while all other broken lines are included for the purpose of illustrating portions of the can speaker housing; the broken lines form no part of the claimed design.
